TOY AIRPLANE

Wilburt Marshall, Rte. 1, Box 61,
Carrizo Springs, Tex. 78834

Continuation of design applications Ser. No. 8,349, Aug.
22, 1967, and Ser. No. 8,348, Aug. 22, 1967. This appli-
cation May 16, 1968, Ser. No. 12,555

Term of patent 7 years

Int. Cl. D21—02; D12—07

U.S. Cl. D34—15

FIG. 1 is a side elevational view of one embodiment of toy airplane, showing my new design.

FIG. 2 is a top plan view of FIG. 1.

FIG. 3 is a rear elevational view of FIG. 1.

FIG. 4 is a side elevational view of another embodiment of the design wherein the propellor and its mounting have been omitted.

FIG. 5 is a top plan view of FIG. 4; and

FIG. 6 is a rear elevational view of FIG. 4.

This application is a continuation of co-pending applications D. 8,348, filed Aug. 22, 1967, and D. 8,349, filed Aug. 22, 1967, now abandoned.

I claim:

The ornamental design for a toy airplane, as shown and described.
